UNITED STATES PATENT OFFICE.

CONNIE BLAISDELL, OF RUMFORD, MAINE.

LEAD-PIPE-BENDING DEVICE.

Application filed July 20, 1923, Serial No. 652,842. Renewed November 2, 1926.

My invention relates to a device for bending lead pipe and the like and particularly for forming sharp bends such as are formed in S traps and the like and for measuring the angles or the amount of bend put into the pipe for producing uniform results when a series of pipes are to be bent to the same extent.

Lead pipes are usually bent around pins or posts and without any accurate means of indicating just the extent of the bend and for the purpose of preventing flattening, the pipe is usually filled with sand, resin, or a coiled spring before being bent, these non-flattening devices being removed after the bend is made.

My invention relates to a framework upon which the pipe may be supported by a pair or saddles which are pivoted in position so that they will bend as smoothly and easily as the pipe bends with a follower which acts to force the middle portion of the pipe downward between its two supporting saddles to form a generally U-shaped or V-shaped bend. The follower is forced downward by a power screw engaging a nut connected with the frame of the machine by pivoted tie rods with means by which the pipe supporting saddles may be closed together or drawn apart to bring the supporting points of the pipe at varying distances.

My invention is illustrated in the accompanying drawings in which:—

Figure 1 is a side elevation of the device and,

Fig. 2 is a plan looking down onto the device.

Referring to the drawings, the supporting framework is made up of two side bars 1 and 2, preferably made of flat metal bars having a series of recesses 3 cut into the lower edge of each bar and extending upward about half the width of the bar. Supporting the side bars at one end are uprights 4 secured to the end of the bars with a wide foot flange 4' for holding the bar in an upright position. A similar upright 6 sustains the other end of the side bars with a broad bearing 6' similar to the bearing 4'. The pipe to be bent is supported on two saddles 7 and 8 which are pivoted to the side bars and hollowed out to substantially fit around the pipe 9 designed to be bent by the machine. The saddle 8 is pivoted between the two side bars at one end of the machine by means of a pivot 10 which extends entire-

ly across the machine, passing through the saddle 8, and the saddle 7 is pivoted to the two bars by means of a pivot 11, the ends of which pass through the saddle and through the recesses 3 in the side bars. The pivots 10 and 11 besides passing through the side bars and the saddles pass through the lower end of two pairs of tie rods 13, the upper ends of which are pivoted to a nut 14 raised some distance above the machine to enable the tie rods 12 and 13 to be spread apart a greater or less distance as desired so that the pivot 11 may catch in one or the other of the recesses 3.

The bend in the pipe is made by forcing downward the central portion between the saddles 8 and 7.

For this purpose, a follower 15 is recessed on its lower side to fit around the pipe and it is pivoted to the lower end of an upright power screw 16 which passes through and engages the nut 14.

At the upper end of the power screw 16 is a suitable handle 7 preferably formed by bending a loop in the screw itself.

There is shown at the end of the bent pipe section a portion of the spiral spring 18 which is designed to hold the pipe round and to prevent it from collapsing.

Means are provided for indicating the angle made by the bend of the pipe, and as herein shown, a disk 20 is pivoted on the end of the pivot 10 so as to revolve freely and be turned readily by hand. Pivoted on the end of the pivot 10 is a hand or pointer 21, one end of which is sharpened to form a pointer which remains in contact with the disk 20 while the other or rear end is bent round and secured to the saddle 8 by means of a strap 22.

Thus, the turning of the saddle 8 on its pivot 10 brings the indicator into the same position as the saddle 8.

By suitable divisions on the disk 20, the disk will indicate the angle to which the saddle 8 and consequently the pipe resting in the saddles assumes.

By dividing the disk into quadrants and sub-dividing the quadrants with one of the squared lines of the circle turned to horizontal position, the number of degrees indicated by the pointer on the quadrant will indicate the angle formed by the lead pipe.

It will be seen that by the use of the various recesses or notches 3 formed in the side bar 1, the saddles 7 and 8 may be separated

or moved together according to the length of the bend desired to be made in the lead pipe.

A bending device constructed as herein shown is of great use to plumbers and others having occasion to bend lead pipe for various purposes such as traps, elbows, etc.

I claim:—

1. In a machine for bending lead pipe and the like, the combination of a frame formed of a pair of side bars, supporting means for said side bars, a pair of pipe supporting saddles pivoted between said side bars and to the same, a nut above said side bars, tie rods connecting said nut with pivoting points of said saddles, a follower for forcing the central portion of said pipe downward, a screw for acting on said follower to depress the same, a handle for said screw and an

indicator for indicating the amount of the bend formed in the pipe. 20

2. In a machine for bending lead pipe and the like, the combination of a frame formed of a pair of side bars having a series of recesses formed in its lower edge, a support 25 for said bars, a pipe supporting saddle pivoted between said bars at one end, a second pipe supporting saddle having pivots engaging opposite slots in said bars, a follower for resting on said pipe between said 30 saddles, a nut above said bars, tie rods pivoted to said nut at their upper ends and to the pivotal points of said saddles at their lower ends, a power screw engaging said nut and said follower for forming the bend in 35 the pipe.
